UNITED STATES PATENT OFFICE

ALBERT G. ZINMAN, OF BROOKLYN, NEW YORK

PLUG ATTACHMENT

Application filed February 14, 1929. Serial No. 339,778.

This invention relates to improvements in electric plug devices, and particularly, to devices of this class, applied in association with electric plugs, used in the ordinary sockets on 5 electric appliances, household appliances and wall sockets.

One of the difficulties encountered in the present time in the use by the housewife of electrical necessities, resides in the tendency 10 of the electrical connector cords of the plug, becoming torn or loose at the contacts, or separated at the contacts leading to the prong members therein, due to the fact that the user, particularly, women, in removing the 15 plug from the socket, does such operation by grasping the electric cord, instead of the plug proper, which due to its size and shape, cannot be grasped readily. Further, the women users by nature, have a fear and aversion to 20 towards touching electrical contacting or carrying mechanisms, and consequently, fearing that a shock or other accident will happen if the plug is withdrawn from the socket by grasping, and will in most cases grasp the 25 cords and withdraw the plug from the socket in that manner.

It is an object of this invention therefore, to provide for an accessory or associated element, which can be attached either separably 30 or fixedly to the base of the plug, and which has thereon, means whereby the user may remove the plug from the socket without touching the plug or electric cords leading thereto.

Specifically, it is an object of this invention, to provide for a novel element in the 35 form of a disk, having therein apertures for the passage therethrough of the conducting prongs of a plug, which disk is adapted to rest against the base or face of the plug next 40 adjacent the face of the socket, which element, has associated therewith, a ribbon or other gripping member, whereby a force exerted upon the ribbon will be transmitted to the element and to the socket, to the plug 45 across the face or base thereof, whereby the plug may be removed from the wall socket, or other socket, without in any way affecting the physical or electrical condition of the connecting cords, in such plug.

Further, it is an object of this invention, to

provide for a novel form of gripping member in association with the disk, as applied to the face or base of a plug, which gripping member passes directly across or is imbedded within the surface of the disk, preferably 55 along the exterior surface thereof, whereby the drawing upon such ribbon, by the user will impart a pull or pressure all along the face of the disk and of course the plug, whereby by the removal of the plug from the socket, 60 that is, the separation of the prongs of the plug from the resilient contact elements in the socket is carried on through a single actuation or pull by the operator.

These and other advantages, capabilities, 65 and features of the invention will appear from the subjoined detail description of one specific embodiment therefor illustrated in the accompanying drawing, in which

Figure 1, is a perspective view of a plug, 70 fitting into a wall socket with the appliance positioned in actual use.

Figure 2, is a side elevation in section, taken along lines 2—2 of Figure 1;

Figure 3, is a plan view of the device, prior 75 to the application of the plug;

Figure 4, is a front elevation in section taken along lines 4—4 of Figure 3;

Figure 5, is a plan view of a modified form 80 of the device;

Figure 6, is a front elevation in section, 85 along lines 6—6 of Figure 5;

Figure 7, is a plan view of a further modified form of the device;

Figure 8, is a side elevation in section taken 90 along lines 8—8 of Figure 7.

Referring to the reference characters in the drawing, numeral 10, represents an attachable plug head of the construction commonly used for sockets of various types, particularly for wall sockets. Numeral 11, represents a socket panel into which the receptacle portion or the adapted portion of the socket (not shown) is positioned.

The device forming the subject matter of 95 this invention, comprises an insulating strip 12, preferably formed of a phenolic condensation product, or vulcanized fibre, usually in the form of a disk having ears 13 thereon, as applied to a wall socket, though it is 100

within the province of this invention to provide for a circular disk as shown in Figures 5 and 6, for application, where the electric light plug is to be inserted into an electric light socket, within a shade. This disk 12, is of comparatively small thickness, and has formed therein a plurality of apertures 14 and 14', through which the conductor prongs extending from the plug member, and fitting into the slots of the socket member (not shown) leading to the contacts therein, are adapted to pass.

As shown in Figures 4 and 7, a plurality of apertures 15 and 15' are provided on opposite sides of the disk and in the plane transverse to that of the apertures 14 and 14', a band or ribbon 16, formed of a nonconducting material, which may be rigid or flexible, as desired, which ribbon 16, passes through both apertures 15 and 15', and is fastened to form a loop as at 19.

As shown in Figure 4, there may be a groove 17, which may be formed between the apertures 14 and 14', and into which groove 25 a band or ribbon 16, may pass, whereby to present a flat contacting surface on both sides of the disk, contacting respectively with the socket receptacle, and with the face or portion of the plug from which the prongs 14 project.

As shown in Figures 5 and 6, the insulating member is circular, so that the plug carrying the disk may be applied to the socket portion of lamp sockets, wherein the space 35 for manipulation of the plug is limited. In this structure, a groove 17 is formed across the disk and the ribbon 16 is fastened therein, preferably by pasting, riveting or eyeletting.

It should be noted (as shown in Figure 2) that the band 16, extends substantially completely, across the surface of the disk and the plug, between the prongs, so that a drawing action on the free end of the band 16, will 45 cause a force to be applied equally all along the face of the disk, whereby the plug will be withdrawn throughout a positive pull, throughout the central zone along its diameter, whereby complete withdrawal of the 50 plug from the socket, will be assured, without any breakage of plug parts, or short circuiting due to improper electrical disconnection.

Likewise, through the use of this invention, 55 it can be seen that the electrical conductor cords, or cables 18, are not handled or acted upon by the user, in the insertion and withdrawal of the plug, whereby the mechanical electrical contact of the cord ends, with the 60 conductors in the plug, cannot be affected through sudden pulling forces exerted thereon.

It is obvious that various changes and modifications may be made to the details of construction without departing from the general

spirit of the invention as set forth in the appended claims.

I claim:

1. An attachment for electric plugs, comprising a disk, having a groove centrally thereof, an aperture on each side of said groove for the passage therethrough of the prongs of a plug, the disk being adapted to be positioned adjacent the base of the plug, an aperture at each extremity of said groove, and a ribbon positioned in said groove and having its ends passed through the apertures in said groove, the said ends being tied or knotted, whereby the application of force to said ribbon is transmitted to the surface of the disk and to the plug, whereby the same may be displaced from a wall socket.

2. An attachment for electric plugs, adapted for attachment with the plug, without altering the structure thereof, said attachment comprising a disk, adapted to be mounted on the base of said plug, and provided with apertures for the passage therethrough of the prongs projecting from said plug, a groove extending across said disk, in the area between said apertures, and a band fixed in said groove and having a loop forming a part thereof, whereby the plug and the disk carried thereby may be displaced from a socket.
